UNITED STATES PATENT OFFICE.

ADAM MARCINIAK AND KAZIMIERZ JACHOWSKI, OF NEWARK, NEW JERSEY.

COMBINED IRONING-BOARD AND STEP-LADDER.

1,198,739.

Specification of Letters Patent. Patented Sept. 19, 1916.

Application filed March 8, 1916. Serial No. 82,841.

To all whom it may concern:

Be it known that we, ADAM MARCINIAK and KAZIMIERZ JACHOWSKI, subjects of the Czar of Russia, residing at Newark, in the 5 county of Essex and State of New Jersey, have invented certain new and useful Improvements in Combined Ironing-Boards and Step-Ladders, of which the following is a specification.

10 This invention relates to new and useful improvements in combined ironing-board and step-ladder.

The primary object of the invention is the provision of an article specially designed 15 for household use being adaptable as an ironing-board of extreme strength but readily shiftable whenever desired into a secure form of step-ladder.

A further object of the invention is the 20 provision of a foldable step-ladder adapted for shifting the steps thereof in direct alinement between the side braces of the ladder as well as the struts thereof for forming a board serviceable for ironing and similar 25 purposes having substantially smooth opposite faces.

A still further object is to provide a combined ironing-board and step-ladder that is inexpensive and easy to manufacture but 30 which at the same time possesses great strength and utility when positioned for use as either of the articles named, being compactly folded in its board formation for storage and transportation purposes.

35 With these general objects in view and others that will appear as the nature of the invention is better understood, the same consists in the novel combination and arrangement of parts hereinafter fully described, 40 illustrated in the accompanying drawings and then claimed.

In the drawings forming a part of this application and in which like designating characters refer to corresponding parts 45 throughout the several views, Figure 1 is a side elevation of the device set up for use as a step-ladder. Fig. 2 is a front elevation thereof. Fig. 3 is a detail sectional view taken upon line III—III of Fig. 1 when the 50 device is folded. Fig. 4 is a sectional view taken upon line IV—IV of Fig. 1. Fig. 5 is a central longitudinal sectional view of the device when in its closed ironing-board arrangement, and Figs. 6 and 7 are perspective 55 views of the upper portion of the device set

up as a step-ladder taken forwardly and rearwardly thereof respectively.

Referring more in detail to the drawings, side rails 10 are arranged in parallelism having a rectangular end plate 11 secured there- 60 between at the ends thereof and constituting the top of the step-ladder as well as the head of the ironing-board. Side struts 12 are pivoted at their adjacent ends to the outer end of the plate 11 and the adjacent ends of the 65 rails 10 by means of a pivot rod 13 extending transversely through the said members, it being understood that the struts 12 when folded at the opposite sides of the rails 10 have their forward and rear edges lying flush 70 with the edges of the rails 10 as well as the forward and rear faces of the plate 11.

A plurality of steps 14 are pivoted between the rails 10 by means of transverse rods 15 extending through the said rails and 75 steps, the steps being thus foldable inwardly with their oblique edges 16 in contact with each other and with the adjacent inner edge 17 of the plate 11 which is correspondingly beveled, thus providing substantially smooth 80 surfaces upon both faces of the device, as best illustrated in Fig. 5 of the drawings, it being understood that the steps 14 are of the same thickness as the plate 11 therefore having their opposite faces lying flush with the 85 forward and rear edges of the rails 10 and struts 12 when the device is in its folded position.

Opposite operating rods 18 pivotally connect the outer edges of the steps 14 being at- 90 tached thereto as at 19 so that by longitudinally moving the rods 18, the steps 16 are shifted for arranging the same either in their folded board formation or in their un- 95 folded step arrangement. Links 20 are piv- 95 otally connected as at 21 to the rails 10 in cut away inner portions 22 of the said rails and have pivotal connections as at 23 at their free ends with the upper ends of the operating rods 18, as best illustrated in Fig. 100 4 of the drawings.

When the device is set up as a step-ladder, the struts 12 are separated from the rails 10 and the steps 14 are arranged in parallelism, the elements being properly adjusted to 105 bring the pivotal openings 24 of the link connections 23 in alinement with the trans- 105 verse perforations 25 extending through the struts 12 adjacent the upper ends thereof and thus allowing a locking bar 26 to be 110

positioned therethrough and secured by means of winged set nuts 27 screw-threaded upon the opposite ends of the said bar.

From this detailed description of the invention it will be seen that when the device is set up as a step-ladder as illustrated in Fig. 1 of the drawings, the bar 26 imparts strength and rigidity to the device by means of the spacing links 20 as well as the rods 18, the latter retaining the steps 14 in their spaced operative relations. When desired to change the formation of the device to its flat arrangement serviceable as an ironing-board, one or both of the nuts 27 is removed and the bar 26 withdrawn which allows the steps 14 to be folded between the rails 10 with the rods 18 lying within the longitudinal edge grooves 28 at the rear of the rails 10, while the links 20 are positioned within the cut away portions 22 of the rails. The struts 12 being released are readily folded at the opposite sides of the rails 10 and retaining screws 29 are inserted through the lower ends of the struts 12 and 25 through alining openings 30 in the lower ends of the rails 10 so that the unthreaded reduced ends 31 of the screws will seat within sockets 32 arranged in the adjacent opposite sides of the lowermost step 14.

It will thus be apparent that by substantially reversing the operation, the device may be changed from its board formation to that of the ladder, it being only necessary to remove the screws 29 and shift the struts 35 12 and steps 14 in the manner hereinbefore described, then placing the bar 26 in its operative retaining arrangement and applying the locking screws 27 thereto.

A strong and efficient device is thus provided serviceable for household use and be-

ing compact in its arrangement when positioned as a board employable for ironing or other purposes.

While the form of the invention herein shown and described is what is believed to be the preferable embodiment thereof, it is nevertheless to be understood that minor changes may be made in the form, proportion and details of construction without departing from the spirit and scope of the invention as hereinafter claimed.

What is claimed as new is:—

A device of the class described comprising spaced rails, a spacing plate secured between the rails at one end thereof and having its opposite faces lying flush with the rails and provided with an oblique inner edge, flat members of the same thickness as the plate foldably pivoted in spaced relations between the rails and having engageable beveled edges, the flat members, plate and rails having opposite substantially smooth faces when the flat members are in their folded relations, opposite operating rods for the flat members pivotally connecting the outer edges thereof and disposed parallel with the rails, links pivotally connecting the upper ends of the rods with the rails, struts positioned outwardly of the rails and having their adjacent ends pivoted to the outer end of the plate and the adjacent ends of the rails, a locking bar extending through the struts and through the pivotal connections between the rods and the links, and means for retaining the struts and spaced rails in closed position.

In testimony whereof we affix our signatures.

ADAM MARCINIAK.
KAZIMIERZ JACHOWSKI.
